AMPLIFIER GAIN CONTROL

Walter van B. Roberts, Princeton, N. J., assignor
to Radio Corporation of America, a corporation
of Delaware

Application January 31, 1940, Serial No. 316,476

7 Claims. (Cl. 179—171)

My present invention relates to gain control circuits for amplifiers, and more particularly to an automatic amplifier gain control circuit of minimum signal distortion.

It is known in the prior art to provide a signal amplifier tube with an auxiliary anode which functions as a so-called "waste" electrode, and to control the amplifier gain by diverting a variable fraction of the electron stream from the output electrode to the waste electrode while keeping the total cathode current constant. In this mode of gain control the operating characteristic of the working section of the tube is altered solely in the scale of output current, and not in the shape of the curve. In this way it is possible variably to amplify weak signals while operating at all times on the most linear portion of the tube characteristic curve.

According to my present invention there is provided a simple tube structure for securing the aforesaid distortionless gain control, and the entire circuit being well adapted to different types of gain control action.

It may be stated that it is an important object of my invention to provide a signal amplifier provided with a control grid assembly capable of producing a plurality of sheets, or beams, of electrons, and an anode structure similar in structure, and so related, to the grid assembly that upon appropriate biasing of the grid assembly the beams may be variably deflected between a pair of independent systems of the anode assembly.

Still other objects of the invention are to improve generally the efficiency and simplicity of automatic gain control circuits, and more especially to provide such circuits in an economical fashion.

The novel features which I believe to be characteristic of my invention are set forth in particularity in the appended claims; the invention itself, however, as to both its organization and method of operation will best be understood by reference to the following description taken in connection with the drawing in which I have indicated diagrammatically a circuit organization whereby my invention may be carried into effect.

Referring now to the accompanying drawing, there is shown a signal detection system providing an audio voltage amplifier embodying the invention. While the invention is not limited in any way to audio frequencies, the specific illustration is of an audio amplifier since it is considered that the ideal gain control should operate on the audio amplifiers without distortion.

Hence, numeral 1 denotes a rectifier, such as one of the diode type, having its anode 2 connected to the high potential side of resonant input circuit 3. The cathode 4 is connected to the low potential side of input circuit 3 through a load resistor 5 shunted by a carrier frequency bypass condenser 6. The midpoint of resistor 5 is grounded so that the anode and cathode ends of the resistor may assume increasingly negative and positive potentials with carrier amplitude increase.

The input circuit 3 can be coupled to any signal source. For example, if the rectifier is embodied in a superheterodyne receiver, the circuit 3 will be tuned to the operating intermediate frequency (I. F.) of the system. The circuit feeding the circuit 3 may be the I. F. output circuit of an I. F. amplifier. However, the system could be a tuned radio frequency receiver, and in such case the circuit 3 would be variably tuned over a signal frequency range. Assuming, then, that audio modulated carrier voltage is rectified, there will appear across the load resistor 5 modulation voltage and direct current voltage. The modulation voltage is impressed upon an audio amplifier network including at least one tube 7 constructed as shown in the drawing.

The tube electrodes have been greatly magnified in order to show clearly the manner of construction of the electrodes. Within the tube envelope is an electron emission element 8, such as the usual tube cathode, and the latter is surrounded by a control grid assembly composed of double, interleaved turns. In other words, the grid assembly is constructed as a double grid spiral. The grid turns 9, shown as small circles, are to be understood as providing one spirally-wound grid, while the turns 10 shown as black dots of equal diameter provide a second interleaved spirally wound grid.

Cathode 8 is connected to ground through a usual biasing resistor 11 shunted by a bypass condenser 12. Grid 10 is connected by lead 13 and filter resistor 14 to the negative, or anode, end of resistor 5. The grid 9 is connected by lead 15 and filter resistor 16 to the cathode, or positive, end of resistor 5. These connections 13—15 provide the direct current voltage, or automatic biasing, connections to grids 9 and 10. The normal bias of grids 9 and 10 is established by bias voltage developed across resistor 11. In the absence of carrier voltage grids 9 and 10 are at the same negative potential equal to the normal bias, and, therefore, exert equal control on

the electron beams, or sheets of electrons, passing between successive grid turns.

Audio modulation voltage developed across resistor 5 is impressed equally and cophasally upon grids 9 and 10 by a slidable tap 16' connected between the resistor 5 and the junction of condensers 17 and 18. The latter are in series between the grid ends of resistors 14 and 16. The condensers 17 and 18 have a low impedance to audio voltage components, but block the direct current voltage components. The slidable tap 16' may be employed between ground and either half of resistor 5. It will be observed that grids 9 and 10 are arranged in a manner similar to known coplanar grids.

The anode structure, or assembly, consists of a pair of similarly arranged interleaved turns. For example, numeral 20 denotes the turns of the "waste" electrode, while numeral 21 designates the turns of the useful output electrode. The turns 20 and 21, therefore, provide a pair of interleaved, spirally wound turns concentric with the interleaved grids 9 and 10. The arrangement is such that each of turns 20 is in substantial alignment with each turn 10 and 9, while each turn 21 is in substantial alignment with a line passing half way between successive turns 9 and 10. Numeral 30 designates arrows which should be understood as representing normal paths of the electrons in each sheet, or beam, of electrons. It will be noted that the beams of electrons are directed at the turns of output electrode 21 when the grids 9 and 10 have the normal equal negative biases applied thereto.

The output electrode 21 is connected to a source of positive potential through a load resistor 40, and the amplified voltage is transmitted through audio coupling condenser 41 to succeeding audio voltage utilization circuits. The waste electrode 20 is connected to a positive voltage source by a resistor 50. It is to be understood that the positive potentials applied to electrodes 20 and 21 will be so relatively proportioned that, with normal biases on grids 9 and 10, the beams 30 will be formed and concentrate, or impinge, on the output electrode 21. This would be the maximum amplification, or weak signal, state of amplifier 7.

Assuming, now, that the carrier amplitude at the carrier input circuit increased in magnitude, the grid 9 would be biased in a positive polarity sense, while grid 10 would be made increasingly negative. The turns of grids 9 and 10 would act as beam deflection elements, since each turn of grid 10 would repel its adjacent beam from the impinged turn of output electrode 21 towards an adjacent turn of electrode 20. In the same way each turn of grid 9 would attract, or draw, its adjacent beams towards the turns of electrode 20 in alignment therewith. The dotted arrows 30' show the manner in which a pair of beams are deflected towards, or diverted to, a turn of electrode 20 by the attraction exerted by the positively biased electrode 9, and the repulsion exercised by the negatively biased electrode 10.

The diversion of the electron beams to the turns of the waste electrode 20 increases with increasing carrier amplitudes. Hence, the audio gain would be correspondingly decreased. The rate of diversion, as well as the extent thereof, can be controlled to vary the output volume level in any predetermined manner. The advantage of varying the biases of both control electrodes 9 and 10 in differential manner resides in the

fact that the total cathode current is maintained substantially constant. It will, therefore, be seen that the electron beam deflection means is a double spiral control device, the turns of one group being insulated from the turns of the other. Each group of turns, or each control electrode, has a separate biasing connection, although a common bias voltage could be applied to both control grids. The impedances 40 and 50 may be made similar in order to preserve the desired distribution of current between the two anode groups. So long as the signal voltage is small compared to the bias applied to the control electrodes the beaming action is not much affected. Of course, negative voltage at the anode end of resistor 5 may be used as volume control bias for amplifier stages preceding detector 1. Similarly, the positive voltage at the cathode end of resistor 5 could be used for gain expansion control of any amplifier of the receiving system.

Again, the direct current potential of only one of the beam deflection electrodes (9 or 10) may be varied. The control bias may then be positive or negative. In this case the control bias should have sufficiently large magnitude to deflect the beams appropriately. For example, the connection 15 could be dispensed with, and the bias connection 13 would then act as a gain reducing means as the signal carrier amplitude increased. If, however, the connection 13 were eliminated and the bias connection 15 only used gain reduction would also be had. Of course, in either case, the entire drop across resistor 5 could be used.

Automatic gain expansion is had by simply reversing the connections of output loads 50 and 40 to output turns 20 and 21. By connecting resistor 50 to electrode turns 21, and the output resistor 40 to turns 20, at signal voltage the output would be small, and would increase with signal voltage input increase. By applying audio signal voltage, in this latter expansion function, to grids 9 and 10, and rectifying the audio voltage to secure a direct current voltage dependent on modulation percentage, audio gain expansion is secured.

Signal potentials developed on the two groups of anodes will always tend to oppose the deflection of the beams. This action may be welcomed as a form of degenerative feedback or load reaction, or it may be reduced by interposing an ordinary screen grid between the grids 9-10 and the anodes 20-21. In that case the turns 60 of the screen grid are located midway between each pair of successive anode turns, and slightly nearer the cathode so that the beams are shielded from the influence of one set of anode turns after they have passed the screen wires on the side nearest the other set of anode turns.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In a signal amplifier network, a tube provided with an electron emission element, a plurality of double interleaved anode elements, an output load impedance connected to one set of said anode elements, and a plurality of double

interleaved electron deflection electrode elements arranged in a spaced relation similar to one set of said anode elements, means automatically responsive to signal intensity variations for varying the direct current potential of at least one set of said deflection electrode elements, and other means for applying signal voltage to at least the remainder of said deflection electrode elements.

2. In a signal amplifier circuit, an electron discharge tube provided with a cathode, a pair of anode electrodes, and a pair of electron deflection electrodes, said deflection electrodes each consisting of a plurality of spaced control elements, and the control elements of one deflection electrode being interleaved with the control elements of the other deflection electrode, said anode electrodes each consisting of a plurality of anode elements, and the anode elements of each anode being interleaved with the anode elements of the other anode, the anode elements of one anode electrode being in substantial alignment with the control elements of said deflection electrodes whereby a plurality of electron beams are provided, said beams flowing to the anode elements of the second one of said anodes, means for applying signal voltages to said deflection electrodes, and means adjusting the direct current potential of said deflection electrodes for deflecting said electron beams from the anode elements of said one anode to the anode elements of the second anode.

3. In a signal amplifier circuit, an electron discharge tube provided with a cathode, a pair of anode electrodes, and a pair of electron deflection electrodes, said deflection electrodes each consisting of a plurality of spaced control elements, and the control elements of one deflection electrode being interleaved with the control elements of the other deflection electrode, said anode electrodes each consisting of a plurality of anode elements, and the anode elements of each anode being interleaved with the anode elements of the other anode, the anode elements of one anode electrode being in substantial alignment with the control elements of said deflection electrodes whereby a plurality of electron beams are provided, said beams flowing to the anode elements of the second one of said anodes, means for applying signal voltages to said deflection electrodes, means for deflecting said electron beams from the anode elements of said one anode to the anode elements of the second anode, and said last means comprising a source of signal-derived direct current voltages which is connected to both deflection electrodes to differentially bias them.

4. In a signal amplifier circuit, an electron discharge tube provided with a cathode, a pair of anode electrodes, and a pair of electron deflection electrodes, said deflection electrodes each consisting of a plurality of spaced control grid elements, and the control elements of one deflection electrode being interleaved with the control elements of the other deflection electrode, said anode electrodes each consisting of a plurality of anode grid elements, and the anode elements of each anode being interleaved with the anode elements of the other anode, the anode elements of one anode electrode being in substantial alignment with the control elements of said deflection electrodes whereby a plurality of

electron beams are provided, said beams flowing to the anode elements of the second one of said anodes, means for applying signal voltages to said deflection electrodes, and means adjusting the direct current potential of at least one deflection electrode for deflecting said electron beams from the anode elements of said one anode to the anode elements of the second anode.

5. In a signal amplifier circuit, an electron discharge tube provided with a cathode, a pair of anode electrodes, and a pair of electron deflection electrodes, said deflection electrodes each consisting of a plurality of spaced control elements, and the control elements of one deflection electrode being interleaved with the control elements of the other deflection electrode, said anode electrodes each consisting of a plurality of anode elements, and the anode elements of each anode being interleaved with the anode elements of the other anode, the anode elements of one anode electrode being in substantial alignment with the control elements of said deflection electrodes whereby a plurality of electron beams are provided, said beams flowing to the anode elements of the second one of said anodes, means for applying signal voltages co-phasally to said deflection electrodes, and variable direct current voltage means connected to at least one deflection electrode for deflecting said electron beams from the anode elements of said one anode to the anode elements of the other anode.

6. In an alternating voltage transmission system, an electron discharge tube of the type provided with an electron emission element, an output anode electrode, at least two control electrodes positioned adjacent said emission element and arranged to provide an electron beam flowing between said control electrodes to said output electrode, an auxiliary output electrode of at least two elements in alignment with each of said control electrodes, said auxiliary electrode elements being in alignment with said output electrode in a direction substantially normal to said first alignment, load circuit connected to said auxiliary output electrode, means for applying signal currents upon said control electrodes, and means for varying the potential of at least one of the control electrodes to deflect the electron beam from said output electrode to said auxiliary electrode.

7. In a signal transmission system, an electron discharge tube of the type provided with an electron emission element, an output anode electrode, at least two control electrodes positioned adjacent said emission element and arranged to provide an electron beam flowing between said control electrodes to said output electrode, an auxiliary output electrode of at least two elements in alignment with each of said control electrodes, said auxiliary electrode elements being in alignment with said output electrode in a direction substantially normal to said first alignment, a load circuit connected to said auxiliary output electrode, means for applying signal currents upon said control electrodes, means for varying the potential of at least one of the control electrodes to deflect the electron beam from said output electrode to said auxiliary electrode, said varying means consisting of a rectifier of signal currents, and connections to apply rectified voltage to said one control electrode.
